Specification of Letters Patent.

Patented May 30, 1916.

Application filed January 15, 1915. Serial No. 2,391.

To all whom it may concern:

Be it known that I, ELMER R. CORWIN, citizen of the United States, residing at Chicago, in the county of Cook and State 5 of Illinois, have invented a certain new and useful Improvement in Telephony, of which the following is a full, clear, concise, and exact description, reference being had to the accompanying drawings, forming a part of 10 this specification.

My invention pertains to telephone exchange systems, one feature of the invention relating particularly to party telephone lines upon which are party line stations 15 having signal bells requiring current of differing character or differing ringing circuits whereby any station upon a line may be signaled exclusively of the remaining stations upon such line. In practising this 20 feature of my invention I am able to employ a smaller number of ringing current selecting switches for each link connector than there are kinds of signaling current. These ringing current selector switches are desirably electro-magnetic to enable the automatic or partial automatic operation thereof, though I do not limit myself to this 25 characteristic. To this end I preferably employ switching devices such as manually 30 operated operators' keys each common to the link connectors of a group and each individual to a peculiar kind of current or means for furnishing the same, each key being also 35 peculiar to the bells that are adapted to be operated by the source of current to which such key is individual. For example, let it be 40 assumed that there are three party line stations upon a line having bells which are respectively responsive to alternating currents of fifty cycles, sixteen cycles and sixty-six cycles. There would then be three 45 sources or means for furnishing such current and, preferably, three operators' buttons or keys each for one of such stations and individual to the source of current adapted to 50 operate such bell. As I have practised the invention for three party line service there are desirably two ringing electro-magnets individual to each link connector of a group 55 of link connectors and so interrelated with each other and with three keys that these two magnets are enabled to control the application of calling current from the three sources to the party line connected with the link connector having such magnets for selec-

tively operating the three bells. There is also desirably employed a master switch for interchangeably associating the three keys with the sources of calling current and the link connectors, this master switch being 60 desirably provided with means whereby it will normally rest in connection with an idle link connector and will move from association with this link connector when taken for use to association with a new idle link connector when the master switch has performed its portion of the ringing operation. In the preferred embodiment of the invention the master switch seeks a new idle link connector when the ringing current 70 has been initially applied, the control of the ringing current being desirably thereafter automatically effected independently of the master switch and the ringing buttons. Each link connector is desirably provided 75 with a signal device individual thereto which the master switch operates when it newly comes into association with the link connector having the same so that the operator will know which link connector is 80 next to be newly taken for use.

Another feature of the invention has for its object the provision of means whereby electrically charged lines may be discharged 85 in order that sensitive relay mechanism or other telephone equipment that would be effected by a charged condition of lines may be freed of the influence of such charged condition. This feature of my invention is of particular service in connecting cord circuit 90 or link connector equipment with called lines having bell bridges that include condensers therein, though the invention is of service even though the condensers be absent. In practising the present feature of my invention I provide means for automatically discharging the capacity of the lines after each 95 period of ringing, for the purpose stated, and for rendering the signal bells at called stations more sharply to respond to signaling current.

My invention, in another of its aspects, relates to those telephone exchange systems in which talking battery feed relays are employed for controlling the application of talking battery to connected lines. Such talking battery relays are usually associated with other relays that open and close the lines, though the invention is not to be limited to the employment of these latter re- 105 110

lays. As I have practised the invention these relays are under the control of the master switch which I have provided during the time that the master switch remains in connection with the link connector associated therewith that has been taken for use. After the master switch has performed its function and is moved into association with a new idle link connector these relays are controlled at connected stations and hitherto quickly responded to quick opening and closing of line circuits occasioned, for example, by quick movement of the switch hooks. The battery feed relays are quick to be energized and released and hitherto the other aforesaid relays were also quick to be energized and released. The condition was such that unintentionally quick vibration of the switch hook at a subscriber's station, particularly a called subscriber's station, would be followed by such operation of the two relays associated with the line as to remove the talking battery therefrom and break the connection between subscribers. To avoid this condition I make the aforesaid magnets that directly control the continuity of the telephone lines slow to release so that they will not operate when their lines are quickly opened and closed. The period of release is desirably one second. While this feature of the invention has been employed particularly in connection with battery feed relays I do not wish to be limited to the peculiar form of line continuity controlling relays to which the invention is applied nor to the adaptation of the invention to service in connection with two relays coupled with a line.

I will explain my invention more fully by reference to the accompanying drawing showing a single station line and a party station line and telephone exchange equipment for establishing a controlling connection therebetween.

At station 200 I have shown ordinary telephone equipment including a telephone switch-hook 1, a telephone receiver 2, a telephone transmitter 3, a call bell 4, and a condenser 5, the bell and condenser being shown in permanent bridge while the switch hook is provided with an upper contact that closes the telephone bridge when the switch is relieved of the associate receiver. The equipment at stations 300, 400 and 500 is desirably similar to equipment at station 200, similar parts having similar characters of reference. The call bells 4¹, 4², and 4³, however, which are provided at stations 300, 400 and 500 are not adapted to respond to current of one kind. For purpose of explanation, it may be assumed that these bells are respectively responsive to alternating current of fifty cycles, sixteen cycles and sixty-six cycles. Each of the telephone lines extend to an exchange where it is shown as

terminating in the tip and sleeve line springs of a spring jack 6, though the invention is not to be limited to the form of exchange line termination employed. A line signal lamp 7 is normally included in bridge of each telephone line by means of back contacts of the springs of the associate spring jack.

It being assumed that station 200 is a calling station, the subscriber thereat will remove his telephone receiver from its switch hook to operate the line lamp 7 and the operator will insert the answering plug 8 in the jack 6 of the calling line following this operation by a depression of her listening key 9 to include her telephone set 10 between the answering ends of the tip and sleeve strands of the link connector which she has taken for use. It being assumed that one of the party line stations is to be the called station, the operator will insert the connecting plug 11 in the jack of the party line having such called station (if the party line has tested free), it being explained that the operator has taken that link connector for use whose individual lamp 12 has been caused to glow, by equipment which will later be set forth, to inform the operator that this link connector is next in order to be taken for use. The operator is provided with three manual keys 13, 14 and 15 (the party line being a three station line) which respectively pertain to all bells 4¹ of the system, all bells 4² of the system, and all bells 4³ of the system, and which are respectively individual to sources or means for furnishing alternating current of fifty cycles, sixteen cycles and sixty-six cycles. The keys 13 and 14 each includes a single grounded contact while key 15 includes two grounded contacts. Each of these contacts has a complementary contact normally separated therefrom, the complementary contacts of keys 13 and 14 being connected with wipers 16 and 17 by a master switch while the complementary contacts of keys 15 are respectively connected with these wipers. The wipers 16 and 17 thus constitute elements of a master ringing switch whose sets of waiting contacts are individual to different link connectors, one set of waiting contacts being shown in connection with the link connector to which it is individual while another set of waiting contacts individual to another link connector is not shown in connection with such latter link connector.

The wipers 16 and 17 which are shown as resting in connection with waiting contacts individual to the illustrated link connector bring the ringing relays 18 and 19 (there being two such relays individual to each link connector) into association with the keys 13, 14, and 15. These ringing relays in turn control the various means 20, 21 and 22 for

respectively furnishing alternating current of sixty-six cycles, sixteen cycles and fifty cycles. The alternate contact of the lower intermediate armature switch of relay 19 5 constitutes a terminal for the ringing source 20, the normal contact of this armature switch constituting a terminal for the ringing source 21, while the contact for the upper intermediate armature switch of relay 19 constitutes a terminal for the ringing source 22. The alternate contact of the intermediate armature switch of relay 18 is connected with the lower intermediate armature switch of relay 19 while the normal 10 contact of the former switch is connected with the upper intermediate armature switch of relay 19. The two lowermost armature switches of relays 18 and 19 are connected together and each has as its contact normally separated therefrom the lower terminal of its relay. The upper terminals of the relays are connected together and have a common ground connection through the grounded battery 23 which is preferably 15 common to the exchange but whose illustration is repeated for the sake of clearness of the diagram. If party line station 300 is wanted the operator will depress the key 13 to establish a circuit traceable from the grounded battery 23, the winding of relay 19, the wiper 16 and the waiting contact engaged thereby, the contacts of the depressed key 13, to ground. The relay 19 will thereupon respond to move its armature switches to include the generator 22 (to 20 current from which the bell 4¹ at station 300 is alone responsive) in a circuit traceable from ground, through this generator 22, the ringing timer 24, intermittently brought 25 into circuit with said generator, the contact brush 25 engaging this timer, the then engaged contact of the upper intermediate armature switch of relay 19, the normal contact of the intermediate armature switch of relay 18, the normal contact of the intermediate armature switch of the ringing interrupter relay 26, the sleeve of the connecting plug 11, the sleeve spring of the jack 6 of the party line, to all of the bells upon the party line, thence to the tip spring of the jack 6 of the party line, the tip of the connecting plug 11, the top armature switch of relay 26, to the grounded normal contact of this switch. The bell 4¹ at station 300 is the only one which will respond to this current and is therefore selectively operated. If party line station 400 is wanted the operator will depress the key 14 to establish a circuit traceable from the grounded battery 23, the winding of relay 18, the wiper 17 and the waiting contact engaged thereby, the contacts of the depressed key 14, to ground. The relay 18 will thereupon respond to move its armature switches to include the generator 21 (to current from which the bell 4² at station 400 is alone responsive) in a circuit traceable from ground, through this generator 21, a ringing timer 27, intermittently brought into circuit with said generator, the contact brush 28 engaging this timer, the then engaged normal contact of the lower intermediate armature switch of the now deenergized relay 19, the alternate contact of the intermediate armature switch of energized relay 18, the normal contact of the intermediate armature switch of the ringing interrupter relay 26, the sleeve of the connecting plug 11, the sleeve spring of the jack 6 of the party line, to all of the bells upon the party line, thence to the tip spring of the jack 6 of the party line, the tip of the connecting plug 11, the top armature switch of the relay 26, to the grounded normal contact of this switch. The bell 4² at station 400 is the only one which will respond to this current and is therefore selectively operated. If party line station 500 is wanted the operator will depress the key 15 to establish circuits for the relays 18 and 19 which will be apparent from the foregoing description since one of the complementary contacts of the key 15 is in multiple with the complementary contact of key 13 and the other complementary contact of the key 15 is in multiple with the complementary contact of the key 14. The relays 18 and 19 will thereupon respond to move their armature switches to include the generator 20 (to current from which the bell 4³ at station 500 is alone responsive) in a circuit traceable from ground, through this generator 20, the ringing timer 29 intermittently brought into circuit with said generator, the contact brush 30 engaging this timer, the then engaged alternate contact of the lower intermediate armature switch of relay 19, the alternate contact of the intermediate armature switch of relay 18, the normal contact of the intermediate armature switch of the ringing interrupter relay 26, the sleeve of the connecting plug 11, the sleeve spring of the jack 6 of the party line, to all of the bells upon the party line, thence to the tip spring of the jack 6 of the party line, the tip of the connecting plug 11, the top armature switch of the relay 26, to the grounded normal contact of this switch. The bell 4³ at station 500 is the only one which will respond to this current and is therefore selectively operated.

It is desirable to release the actuated button 13, or 14, or 15, after it has initially completed the selected current to the party line, to which end means are provided for locking the circuit of the energized magnet 18 or 19 or the circuits of both when energized. I may employ the calling subscriber's supervisory relay 31 for this purpose, the windings of this relay being bridged across the cord circuit or link connector in 130

the usual manner but to which relay an extra armature switch 31¹ is added. When this relay is energized the armature switch 31¹ establishes the locking circuit traceable in 5 part from the grounded battery 23, to the engaged contact of this armature switch by way of the relay winding or windings 18, 19 and the lower armature switch or switches of these relays and the contacts 10 engaged thereby. Such circuit is completed from the armature switch 31¹ to the bottom and grounded armature switch of the called battery feed relay 32 by way of the normal contact of this armature switch. The ringing 15 relay 26 was energized owing to the establishment of circuit traceable from the grounded battery 23, the thimble of the engaged party line jack, the heel of the plug received by the jack, the winding of the 20 ringing relay 26, the intermediate armature switch of the called battery feed relay 32, the normal contact of this switch, one or the other or both of the top armature switches of the magnets 18 or 19 according to the 25 energization of these magnets, the contacts of such latter armature switch or switches, the brush 35, the interrupter 36, to ground, the interrupter 36 being so related to the ringing current synchronously operating in 30 interrupters 24, 27 and 29 as to establish a circuit for the relay 26 when the selected ringing generator is out of circuit whereby the magnet 26 will be energized only during the time that no calling current is upon 35 the calling line. The circuit for one or the other or both of the magnets 18 and 19 having been closed according to the signaling current selected, the master switch having the wipers 16 and 17 is stepped into association 40 with a new idle link connector, waiting contacts of another link connector being illustrated below the waiting contacts that are engaged by these wipers. This result is due to the establishment of a circuit traceable from the grounded battery 23, the winding of the motor magnet 33, the back contact of the motor armature of the motor magnet, said armature, the wiper 34 of the master switch, the waiting contact with 45 which the wiper 34 is shown in engagement, to the grounded bottom armature switch and its contact of relay 26 when this relay is energized upon the closure of its circuit at 50 35. The motor magnet 33 will continue in operation until its wiper 34 engages some waiting contact pertaining to some other link connector which is not grounded either at the bottom armature switch of relay 26 of a line being signaled or by way of the 55 intermediate armature switch of supervisory relay 31 (when this relay is energized) and the bottom armature switch of the battery feed relay 32 (when energized), the relays 31 and 32 both being energized 60 65 when the called party has responded. Re-

lay 32 also constitutes a called supervisory relay and relays 31 and 32 are provided with display targets operated by their top armature switches. When the called subscriber responds the signaling circuit is 70 broken at the intermediate armature switch of relay 26 and the locking circuit for either or both of the magnets 18 or 19 is broken at the bottom armature switch of relay 32 whereupon the magnets 18 and 19 75 are restored to normal. These magnets are individual to the illustrated link connector, each link connector having such a pair of magnets in similar circuit association, taps being illustrated from the conductors connected with the contacts of the three upper armature switches of the relay 19 which extend to similar contacts of the relays 18 and 19 pertaining to the remaining link connectors of the group of link connectors to 80 which the master switch is common.

It is desirable to discharge the capacity of the called line after each ringing period, a function which should be accomplished before circuit for the ringing interrupter 90 relay 26 is established at the interrupter 36 in order that the relay 32 may be free of the impairing effect of the capacity of the called line, this relay therefore being free to operate as it is designed to do. To 95 this end each ringing generator 20, 21, 22 (or the ringing generator of the system if there be but one) has individual thereto a short circuiting and grounding device, these devices being illustrated at 37, 38 and 39. 100 Each short circuiting and grounding device includes a grounded segment and a brush for engaging the same; these devices being in the form of disks which are co-axial with the disks 24, 27, 29 and 36 and all of which 105 are mounted upon the shaft of a constantly operating motor 40. But one circuit interrupting and grounding device is employed at a time, each according to the source of current which is included in circuit. 110

The circuit of the short circuiting and grounding device is established just after each ringing period and before the interrupter 36 has brought the magnet 26 into circuit, that is before the called subscriber 115 can bring himself into telephonic communication with the calling subscriber. In other words the order of operation is as follows: The ringing current is first applied during a ringing period, of about a second, 120 the short circuiting and grounding device is brought into operation immediately upon the conclusion of the ringing period and acts for about one-quarter of a second, whereafter the interrupter 36 is brought into play 125 to energize the magnet 26 during a period of three-quarters of a second during which the called party may bring himself into telephonic connection with the calling party. The discharging connection established by 130

either of the devices 37, 38, 39 is traceable from the grounded element thereof, the contact brush intermittently engaged thereby, the upper lead of the particular generator 5 which is employed, thence by one of the circuits previously traced for the passage of ringing current, to ground at the upper armature switch of relay 26. Both sides of the called line are thus grounded and consequently short circuited just after each ringing period and just before the interrupter 36 causes the energization of relay 26. That is this short circuiting and grounding occurs just before the three-quarter period 10 within which the called subscriber may answer, with the result that the called line is discharged in order that the relay 32 may instantly respond when the called subscriber does answer and may not have opportunity 15 to respond to a discharge of the line capacity a result which frequently occurred hitherto at the conclusion of ringing periods. Each period of capacity discharge also prepares the called line for the proper reception 20 of signaling current to operate the signal bell during the next ringing period.

I make the relay 26 slow to release, it requiring preferably three-quarters of a second to effect this result. The called battery 30 relay 32 is sensitive to respond and release and will instantly do so when the called line circuit is opened and closed quickly as, for example, when the switch hook at a called station is flashed. Hitherto the relay 26 35 would be released so as to break the continuity of the telephone connection established at its upper armature switches. By making the relay 26 slow to release the instantaneous de-energization of relay 32 will have no effect thereupon so that the continuity of the telephonic connection established by the relay 26 will not be impaired.

While I have employed the elements 13 to 19 inclusive for effecting the application 45 of signaling current or signaling circuits to party lines, some of the claims are drawn to cover the use of these elements to whatever operative purpose to which they may be put.

While I have herein shown and particularly described the preferred embodiment of my invention I do not wish to be limited to the precise details of construction and circuit arrangement shown as changes may readily be made without departing from the 50 spirit of my invention, but

Having thus described my invention I claim as new and desire to secure by Letters Patent the following:—

1. A telephone exchange system including 55 telephone lines which are inclusive of a party telephone line extending to a plurality of party telephone line stations having signal bells selectively responsive to differing signaling circuits; differing signaling circuits for the selective operation of the afore-

said signal bells; connectors for associating the signaling circuits with the party line; sets of electro-magnetic switching devices, each set individual to a connector and each set composed of electro-magnetic switching 7 devices less in number than the differing signaling circuits; circuit connections co-operating with the electro-magnetic switching devices of each set for enabling them to establish one signaling circuit and separately to 75 establish other signaling circuits; manual switches equal in number to the signaling circuits and provided with circuit connections whereby one manual switch will operate one electro-magnetic switching device of 80 a set, another manual switch will operate another electro-magnetic switching device of such set, and a third manual switch will operate both electro-magnetic switching devices of such set; and a switch for interchangeably 85 associating said manual switches with the sets of electro-magnetic switching devices and the connectors to which they belong.

2. A telephone exchange system including 90 telephone lines which are inclusive of a party telephone line extending to a plurality of party telephone line stations having signal bells selectively responsive to differing signaling circuits; differing signaling cir- 95 cuits for the selective operation of the afore- said signal bells; connectors for associating the signaling circuits with the party line; sets of electro-magnetic switching devices, each set individual to a connector and each 100 set composed of electro-magnetic switching devices less in number than the differing signaling circuits; circuit connections co-operating with the electro-magnetic switching devices of each set for enabling them to 105 establish one signaling circuit and separately to establish other signaling circuits; manual switches equal in number to the signaling circuits and provided with circuit 110 connections whereby one manual switch will operate one electro-magnetic switching device of a set, another manual switch will operate another electro-magnetic switching device of such set, and a third manual 115 switch will operate both electro-magnetic switching devices of such set; and a master switch for interchangeably associating said manual switches with the sets of electro- 120 magnetic switching devices and the connectors to which they belong, said master switch being provided with means for effecting its association with an unemployed connector and thereby the association of said manual switches with such unemployed connector.

3. A telephone exchange system including 125 telephone lines which are inclusive of a party telephone line extending to a plurality of party telephone line stations having signal bells selectively responsive to differing 130

signaling circuits; differing signaling circuits for the selective operation of the aforesaid signal bells; connectors for associating the signaling circuits with the party line; 5 sets of electro-magnetic switching devices, each set individual to a connector and each set composed of electro-magnetic switching devices less in number than the differing signaling circuits; circuit connections co-operating with the electro-magnetic switching devices of each set for enabling them to establish one signaling circuit and separately to establish other signal circuits; manual switches equal in number to the signaling circuits and provided with circuit connections whereby one manual switch will operate one electro-magnetic switching device of a set, another manual switch will operate another electro-magnetic switching 10 device of such set, and a third manual switch will operate both electro-magnetic switching devices of such set; a switch for interchangeably associating said manual switches with the sets of electro-magnetic switching 15 devices and the connectors to which they belong; and signal devices individual to the connectors, said switch being provided with means for effecting the operation of the signal device of the connector with which it comes into association.

4. A telephone exchange system including telephone lines which are inclusive of a party telephone line extending to a plurality of party telephone line stations having signal 20 bells selectively responsive to differing signaling circuits; differing signaling circuits for the selective operation of the aforesaid signal bells; connectors for associating the signaling circuits with the party line; sets of electro-magnetic switching devices, each set individual to a connector and each set composed of electro-magnetic switching devices less in number than the differing signaling circuits; circuit connections co-operating with the electro-magnetic switching devices of each set for enabling them to establish one signaling circuit and separately to establish other signaling circuits; manual switches equal in number to the 25 signaling circuits and provided with circuit connections whereby one manual switch will operate one electro-magnetic switching device of a set, another manual switch will operate another electro-magnetic switching device of such set, and a third manual switch will operate both electro-magnetic switching devices of such set; a switch for interchangeably associating said manual switches with the sets of electro-magnetic switching 30 devices and the connectors to which they belong; and signal devices individual to the connectors, said switch being provided with means for effecting the operation of the signal device of the connector with which it comes into association.

5. A telephone exchange system including telephone lines; connectors for the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; and a switch for interchangeably associating said manual switches with the sets of electro-magnets.

6. A telephone exchange system including telephone lines; connectors for the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; and a switch for interchangeably associating said manual switches with the sets of electro-magnets.

7. A telephone exchange system including telephone lines; connectors for the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; and a master switch for interchangeably associating said manual switches with the sets of electro-magnets; said master switch being provided with means for effecting its association with an unemployed connector and thereby the association of said manual switches with such unemployed connector.

8. A telephone exchange system including telephone lines; connectors for the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; a switch for interchangeably associating said manual switches with the sets of electro-magnets; and signal devices individual to the connectors, said switch being provided with means for effecting the operation of the signal device of the connector with which it comes into association.

9. A telephone exchange system including telephone lines; connectors for the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; a master switch for interchangeably associating said manual switches with the sets of electro-magnets, said master switch being provided with means for effecting its association with an unemployed connector and thereby the association of said manual switches with such unemployed connector.

unemployed connector and thereby the association of said manual switches with such unemployed connector; and signal devices individual to the connectors, said master switch being provided with means for effecting the operation of the signal device of the connector with which it comes into association.

9. A telephone exchange system including telephone lines; connectors for the telephone lines; sets of electro-magnets individual to the connectors; manual switches provided with circuit connections whereby one manual switch will operate one electro-magnet of a set, another manual switch will operate another electro-magnet of such set, and a third manual switch will operate both electro-magnets of such set; and a switch for interchangeably associating said manual switches with the sets of electro-magnets.

10. A telephone exchange system including telephone lines; connectors for the telephone lines; sets of electro-magnets individual to the connectors; manual switches provided with circuit connections whereby one manual switch will operate one electro-magnet of a set, another manual switch will operate another electro-magnet of such set, and a third manual switch will operate both electro-magnets of such set; and a master switch for interchangeably associating said manual switches with the sets of electro-magnets, said master switch being provided with means for effecting its association with an unemployed connector and thereby the association of said manual switches with such unemployed connector.

11. A telephone exchange system including telephone lines; connectors for the telephone lines; sets of electro-magnets individual to the connectors; manual switches provided with circuit connections whereby one manual switch will operate one electro-magnet of a set, another manual switch will operate another electro-magnet of such set, and a third manual switch will operate both electro-magnets of such set; a switch for interchangeably associating said manual switches with the sets of electro-magnets; and signal devices individual to the connectors, said switch being provided with means for effecting the operation of the signal device of the connector with which it comes into connection.

12. A telephone exchange system including telephone lines; connectors individual to the telephone lines; sets of electro-magnets for the connectors; manual switches provided with circuit connections whereby one manual switch will operate one electro-magnet of a set, another manual switch will operate another electro-magnet of such set, and a third manual switch will operate both electro-magnets of such set; a master switch for interchangeably associating said manual

switches with the sets of electro-magnets, said master switch being provided with means for effecting its association with an unemployed connector and thereby the association of said manual switches with such unemployed connector; and signal devices individual to the connectors, said master switch being provided with means for effecting the operation of the signal device of the connector with which it comes into association.

13. A telephone exchange system including telephone lines extending from substations to an exchange; link connectors at the exchange for uniting lines in conversation; a common battery for supplying transmitter current to telephone lines; a battery feed relay for intermittently effecting connection between the lines of unresponsive called parties with link connector equipment; means for discharging the capacity of the lines; and means whereby the capacity discharging means is brought into association with a called telephone line when separated from said link connector equipment.

14. A telephone exchange system including telephone lines extending from substations to an exchange; link connectors at the exchange for uniting lines in conversation; means for intermittently effecting connection between the lines of unresponsive called parties with link connector equipment; means for discharging the capacity of the lines; and automatic means whereby the capacity discharging means is brought into association with a called telephone line when separated from said link connector equipment.

15. A telephone exchange system including telephone lines extending from substations to an exchange; link connectors at the exchange for uniting lines in conversation; a common battery for supplying transmitter current to telephone lines; a battery feed relay for intermittently effecting connection between the lines of unresponsive called parties with link connector equipment; means for discharging the capacity of the lines; and automatic means whereby the capacity discharging means is brought into association with a called telephone line when separated from said link connector equipment.

16. A telephone exchange system including telephone lines extending to an exchange; link connectors for uniting lines in conversation and each normally divided into separated sections; a common battery for supplying the telephone lines with transmitter current; battery feed relays individual to the link connectors and permanently associated with the sections adjacent end sections of the link connectors; means for discharging the capacity of the lines when the link connectors are broken and for there-

after bringing the sections of the link connectors together.

17. A telephone exchange system including telephone lines extending to an exchange; link connectors for uniting lines in conversation and each normally divided into separated sections; a common battery for supplying the telephone lines with transmitter current; battery feed relays individual to the link connectors and permanently associated with the sections adjacent end sections of the link connectors; means for grounding both sides and short circuit-

ing telephone lines to discharge their capacity; and means whereby the latter means is brought into association with a called telephone line upon the conclusion of a ringing period.

In witness whereof, I hereunto subscribe my name this eleventh day of January, 1915.

ELMER R. CORWIN.
